SELECTIVE BLOCKING DEVICE FOR OFFICE TYPEWRITER KEYBOARD

Heinz Wlodarczak, Pforzheim, Germany, assignor to International Standard Electric Corporation, New York, N.Y., a corporation of Delaware

Filed Sept. 26, 1955, Ser. No. 536,601

Claims priority, application Germany Sept. 28, 1954

1 Claim. (Cl. 197—107)

This invention relates to improvements in perforating typewriters by which a tape may be perforated according to a code, and in particular to improvements in perforating typewriters in which the perforating mechanism may be put into or out of action as desired.

Perforating typewriters have particular application in preparing perforated tape for printing telegraph purposes. The tape is then stored until a telegraph line is free and the message can be transmitted. Tape perforated according to the printing telegraph code is frequently used also to control computer apparatus, although other codes may be used for this purpose. In all cases, however, the tape is perforated with a series of holes arranged in a code combination, and a printed record of the message perforated is also obtained.

In order to obtain the maximum efficiency from a perforating typewriter, it is necessary for it to be used for ordinary office correspondence as well as for perforating tape. In the past this has not been possible owing to the fact that the International Teleprinter Code uses the same symbols for letters and for figures, and therefore shift signals have to be inserted before respective sequences of combinations to indicate whether they are letters or figures. No keys are provided on a standard typewriter for these insertions and the only keys available for such function are the standard typewriter case shift keys. The case shift keys then lose their normal function and the typewriter can be used to type either small letters or capital letters, but not both. It is the object of the present invention to provide means by which the typewriter may be adapted for use with a perforator and also be capable of typing both small and capital letters.

It has been chosen to disclose the invention as embodied in a perforating typewriter which may be used in conjunction with a perforating mechanism. When used with the perforating mechanism the usual typewriter left-hand and right-hand case shift keys are utilized separately to perform letter shift and figure shift functions. According to the invention a blocking mechanism is provided, which when operated, responds to the actuation of the left-hand shift key to block certain typing keys and permit actuation of others. Similarly, when the right-hand shift key is actuated, the previously blocked keys are freed while the other typing keys are blocked. The keys that are blocked when the one shift key is actuated may correspond to keys which are to be actuated only when the number shift key is operated during perforating operations and vice versa. When the blocking mechanism is unoperated, the left-hand and right-hand case shift keys operate as is usual in conventional typewriters, except they are operated independently of each other.

The invention will now be described with reference to the accompanying drawings in which:

Fig. 1 shows a schematic plan view of one embodiment of a perforating typewriter according to the invention, in a position for ordinary typing.

2

Fig. 2 shows a side view of the typewriter of Fig. 1 with the blocking mechanism in unoperated position to condition the typewriter for conventional typing.

Fig. 2A shows the blocking mechanism of Fig. 2 in operated position to condition the typewriter for perforation typing; and

Fig. 3 shows a front view of the typewriter of Fig. 1 with the blocking mechanism in the position shown in Fig. 2A.

10 Referring first to Fig. 1, there is shown an ordinary typewriter keyboard, in which the case shift key 1 is to be used as a letter shift key when perforating and the case shift key 2 as a figure shift key. For this purpose the keys 1 and 2, which are normally coupled together on a typewriter, are arranged to operate independently so that either of them can raise or lower the type basket to print a capital letter without causing the other to be operated at the same time. At the side of the typewriter there is provided a locking handle 10 which is used to bring a locking device into operation when the machine is being used for perforating and to disengage the locking device when the machine is used for typing only. When used for controlling the perforating mechanism, only lower case letters and figures 15 can be typed. The nature and operation of the locking device will be described with reference to Figs. 2a and 3.

If the locking handle 10 is rotated in the direction of the arrow shown in Fig. 2 (i.e. anticlockwise), a drawbar 9 is raised. Attached to drawbar 9 is a bar 5 and attached to bar 5 is the locking bar 6, so that the turning of the locking handle 10 causes bars 5 and 6 to be raised from their lowered, approximately horizontal position as shown in Fig. 2 to an approximately vertical position with respect to the keybars. The bar 5 (as 20 can be seen in Fig. 3) is pivoted in bearings 7 and 8, which are provided in the side walls of the typewriter. Bar 5 cannot, therefore, be moved longitudinally (i.e. in the directions indicated by the arrows in Fig. 3). The bar 6 however, is fastened to bar 5 in such a way that 25 it can be moved longitudinally, as will be described below.

In the vertical position of bars 5 and 6, the noses of the teeth such as 15 of locking bar 6 lie immediately below the level of the keybars associated with the typewriter keys. The locking handle 10 is conveniently placed at the side of the typewriter and level with the middle of the keyboard. In order that the locking action provided by locking bar 6 shall be effective upon all the keybars of the typewriter, it is necessary for a typewriter key such as 4 in one of the two upper rows of 30 the keyboard to have its associated keybar 18 extended sufficiently far forward to engage with the locking bar 6 (see Fig. 2).

When the typewriter is being used to operate the 35 perforator, certain keybars have to be locked out of operation. This is done by raising bars 5 and 6 by turning locking handle 10 as already described. The bars 5 and 6 are now positioned vertically below keybars associated with all the typewriter keys. In order that only 40 predetermined keys can be operated in a given position of bar 6, this bar 6 is provided with teeth such as 15, separated by cut-out portions such as 16. Although only a few such teeth and cut-out portions are shown 45 in Fig. 3 it should be understood that they will appear along the whole operative length of bar 6.

Bar 6 is connected to bar 5 by screws 11 (Fig. 3) through oblong holes 12 in itself so that it may be displaced longitudinally with respect to bar 5, i.e. in either 50 of the directions indicated by the arrows. The movement of bar 6 is controlled by the shift keys 1 and 2 which have beneath them cut-out portions of bar 6 including inclined surfaces 13 and 14 respectively. These

inclined surfaces are so arranged that, in any position of bar 6, only one of the shift keys will act on its corresponding inclined surface when depressed.

In Fig. 3, the bar 6 is shown in a position such that the figure shift key 2 can be depressed without making contact with any part of bar 6. The teeth 15 and cut-outs 16 are then in positions such that certain keys (for example, those keys corresponding to characters in the figures case of a telegraph code) are above cut-outs such as 16 and can be operated, while the remaining keys (for example, those keys corresponding to characters in the letters case of the telegraph code) are above teeth such as 15 and are locked. However, if the letter shift key 1 is depressed its keybar will impinge on the inclined surface 13 of bar 6 and displace bar 6 to the left. The teeth and cut-outs will then be in a position such that previously locked keys only can be operated. Subsequent operation of figure shift key 2 will cause its associated keybar to impinge on the inclined surface 14 and cause bar 6 to be moved back to the right to the position shown when only the last-locked keys can be operated. Operation of either of keys 1 or 2 causes the corresponding letter shift or figure shift combination to be perforated in the tape as well as longitudinally operating the locking device as described.

While it would be possible to use one bar only, instead of the bars 5 and 6 as described, the one bar then being capable of rotational movement and longitudinal movement, it has been found more satisfactory to subdivide the movements so that the bar 5 is exclusively responsible for the rotational movement and bar 6 exclusively responsible for the longitudinal movement. In a preferred embodiment of the invention, the rotational movement of bar 5 under the control of locking han-

dle 10 is used to couple the perforating device (which is of known type) to the typewriter.

While I have described above the principles of my invention in connection with specific apparatus, it is to be clearly understood that this description is made only by way of example and not as a limitation to the scope of my invention as set forth in the objects thereof and in the accompanying claim.

What is claimed is:

10. A mechanical blocking mechanism for use in typewriter apparatus to condition the said apparatus for either of two modes of operation and for selectively conditioning said apparatus for either of two kinds of operation within one of said modes, said typewriter apparatus including a first and a second group of typing keys and a first and a second function key, said mechanism including a toothed bar extending transversely beneath said groups of typing keys, means for rotating said blocking mechanism between a first position out 15 of engagement with all of said typing keys and a second position in engagement with one of said groups of typing keys, and means controlled by the said function keys when said blocking mechanism is in said second position for laterally moving said toothed bar into engagement with either of said groups of typing keys.
